(57) **CLAIM**

The ornamental design for a slider device for a resealable closure, as shown and described.

DESCRIPTION

FIG. 1 is a top perspective view of a slider device for a resealable closure in accordance with the present invention; FIG. 2 is a top view of the slider device for a resealable closure;

FIG. 3 is a left side elevation view of the slider device for a resealable closure;

FIG. 4 is a right side elevation view of the slider device for a resealable closure;

FIG. 5 is a front elevation view of the slider device for a resealable closure;

FIG. 6 is a rear end elevation view of the slider device for a resealable closure; and,

FIG. 7 is a bottom view of the slider device for a resealable closure.

The phantom lines in the figures show the remaining portions of the slider device and are for illustrative purposes only and form no part of the claimed design.
